UNITED STATES PATENT OFFICE.

HARRIS B. HOLT, OF PITTSBURGH, PENNSYLVANIA, ASSIGNOR TO ROSEDALE FOUNDRY & MACHINE COMPANY, OF PITTSBURGH, PENNSYLVANIA, A CORPORATION OF PENNSYLVANIA.

FURNACE GRATE.

Application filed August 9, 1927. Serial No. 211,692.

My invention relates to furnace grates, particularly to grates for furnaces whose fire boxes must be accessible through end doors and which must be brought within narrow space limits. The grate structure includes an endless chain grate and it may for instance be applied in replacement of a grate structure of simpler form which, stoked manually through the door of the fire-box, has been built within a space of small vertical extent.

The accompanying drawing is a view in vertical and longitudinal section through the furnace of a steam boiler, in which furnace my invention is embodied.

The fire box 1 of this furnace opens to boiler flues 2. In the front wall of the fire box a door 3 is placed, and this door must be accessible, both for purposes of observation, and, when need be, for the charging of fuel to the grate within. The fire box it may be understood is so situated that a space of say no more than twelve to seventeen inches in vertical extent is available beneath for the arrangement of the grate.

An endless chain grate 4 is shown underlying the fire box. Manifestly such a grate may be brought within the space limits named, but the problem remains, how, leaving door 3 accessible, to make provision for the mechanical stoking of the grate so situated.

This problem I have solved in the manner shown. I have provided a platform 5 at the front of and externally of the wall of the furnace, a platform from which the furnace door 3 is accessible; I have placed this platform, elevated at an interval above the ground level of the structure; I have prolonged the grate 4 beneath and beyond

this platform; and I have placed the hopper 6 through which the grate is mechanically stoked on the farther side of platform 5, the left-hand side of the platform as seen in the drawing, and on the side remote from the furnace wall.

Stated in other words, I have formed by and between platform 5 and the upper face of grate 4 a horizontal extension of hopper 6, within which extension the infed fuel shaped and bedded is advanced to pass through the furnace wall and enter the fire box.

By my invention, new installations may be made with economy of space, and old installations in which space is limited may be newly equipped with endless-chain grates.

I claim as my invention:

1. A furnace with a door in its front wall, a platform external to the furnace wall, from which the said door is accessible, a fuel hopper arranged on the side of the platform remote from the furnace wall, and a grate of endless chain type whose upper horizontal reach is continued from beneath the hopper, beneath the said platform, and through the furnace wall to the chamber within.

2. A furnace with a door in its front wall, a platform external to the furnace wall, from which the said door is accessible, a fuel hopper arranged on the side of the platform remote from the furnace wall, and a grate of endless chain type whose upper horizontal reach extends beneath said platform and through the furnace wall to the chamber within, said platform and grate cooperating to form a horizontal extension of said hopper.

In testimony whereof I have hereunto set my hand.

HARRIS B. HOLT.
